(57) **CLAIM**

The ornamental design for a rear door panel for vehicles, as shown and described.

DESCRIPTION

1. Rear door panel for vehicles

1.1 is a perspective view of a tailgate panel for vehicles showing our new design;

1.2 is a front elevation view thereof;

1.3 is a back elevation view thereof;

1.4 is a left side elevation view thereof;

1.5 is a right side elevation view thereof;

1.6 is a top plan view thereof; and

1.7 is a bottom plan view thereof.

This article concerns the outer panel of a rear door of a vehicle, and can be opened and closed from both sides (left and right sides).
